UNITED STATES PATENT OFFICE.

JAKOB STOCKER, OF BERNE, SWITZERLAND.

WEIR, LOCK, AND THE LIKE.

1,246,007.

Specification of Letters Patent.

Patented Nov. 6, 1917.

Application filed July 1, 1912. Serial No. 707,060.

To all whom it may concern:

Be it known that I, JAKOB STOCKER, a citizen of the Swiss Confederation, and residing at Berne, Switzerland, have invented 5 certain new and useful Improvements in Weirs, Locks, and the like, of which the following is a specification.

My invention relates, in general, to weirs or locks, and has more particular relation to 10 movable weirs or lock gates of the type in which a dam or gate is movable transversely across a stream.

The adoption of the principle of well-known sliding lock-gates in weirs leads to 15 various advantages not obtained in the usual known constructions. Among such advantages I may mention, firstly, the possibility of entirely opening the water-way at high water and for navigation; secondly, the weir 20 can be safely operated from the banks; thirdly, the possibility of regulating the weir quickly and with comparatively little power because the gate is moved only transversely of the current; and, fourthly, facility of 25 making repairs because all moving parts can at any time be drawn out of the water into a chamber in the bank and no moving parts have always to remain in the water.

The same principle can also be advantageously applied to the guidance and movement of platforms as a substitute for ferries.

A primary object of my invention is to apply the said principle to both weir and ferry plants.

35 A further object is the provision of a weir or gate of improved construction, and of means for efficiently moving the weir or gate back and forth across a stream and into and out of one or more chambers in the banks 40 of the stream.

A further object is to provide improved guiding means for a movable weir or dam, or lock gate, which are not liable to be clogged by sand or silt, or to be injured by shingle or 45 debris, or ground ice, and which are capable of resisting considerable upstream pressure, both while the weir or dam is being moved back and forth across the stream and is in effective position for holding back the water.

50 One illustrative embodiment of my invention, as applied to a movable weir is represented, by way of example, in the accompanying drawing, wherein:—

Figure 1 is a sectional elevation showing 55 my improved means, and

Fig. 2 a sectional plan view diagrammati-

cally showing the entire arrangement on a smaller scale.

On the bed of a stream, as by being secured to a block of stone or concrete with 60 which the bed of the stream may be lined, is a firmly anchored ground rail 1, a portion of which projects downstream over a cut-away step in the bed or block to which the ground rail is anchored. The projecting portion of the ground rail 1 is provided, on its under side, with one or more downwardly projecting flanges along which are adapted to run guide rollers 2 of a plurality of carriages each carrying a retaining wall 70 3. These rollers impart horizontal thrust to the rail 1 when water is impounded on the upstream side of the weir or dam, the rollers being, preferably, slightly conical, as shown, to engage a beveled side of the downwardly 75 projecting flange of the rail 1. Rails 4, 5, on which rollers 6, 7 of the retaining carriages run, are fixed in position on the downstream side of rail 1, as by being let into the stone or concrete with which the bed of 80 the stream is lined. The weight of the carriages and the reaction-pressure of the projecting rail act opposite to the tilting moment about the lower edges of the carriages and maintain the same in position. 85

There are no parts extending into the stream on the upstream side of the guide rail 1, and there are no recesses formed vertically in the bottom that can be damaged or obstructed. The shingle or debris is carried forward over the suitably inclined bed of the lower level not only by the water falling over the step, but especially by the current of water which forms in front of the first carriage. If necessary, means, such as 90 sweepers, may be provided for clearing the tracks or rails. The proper guidance of the carriages may be effected in various ways. In the present embodiment the rollers 6 have a guide flange for holding the carriage 100 against upstream movement, the rollers 2 acting against the flange of the rail 1 to limit downstream movement.

The chamber 8 for receiving the carriages constitutes a sluiceway which may extend 105 wholly at right angles to the stream, when but one or a comparatively small number of retaining carriages is employed. In case there are several carriages or weir sections, the chamber 8 may comprise a part at right 110 angles and a part parallel to the stream, connected by a curved part of comparatively

easy curvature, as shown in Fig. 2. The chamber 8 may communicate with the upper level of the stream by means of a channel 14 which may be provided with a gate for cutting off the passage of water. The chamber 8 and channel 14 may communicate with the lower level of the stream by means of a channel 15, a gate 13 serving to cut off such communication, when desired. The ground rail 1 preferably extends throughout the whole or a considerable portion of the chamber 8. When there are a plurality of carriages, they are preferably hinged together on one longitudinal side, and detachably coupled together on the other side, in order that they may be uncoupled to pass the curve in the sluiceway 8. The carriages form a rigid barrier which can be driven from and drawn to the bank as by means of one or more gears 10, fixed in position on the bank and suitably driven, and a toothed rack 9, a section of which is mounted on each of the retaining carriages.

For moving the carriages or weir sections in both directions, the pressure of the water of the upper level may be utilized. In the present case, the said pressure can act on a pressure wall 11 fitted to move in the chamber 8 to force the carriages out into the stream, at which time the channel 15 is closed by a gate 13, and the channel 14 is open. When drawing back the carriages, however, the channel 14 is closed and the channel 15 open. Flooding could thus be avoided in a simple manner. The weir can be provided with flood-gates 16 for releasing ice and floating material without its being necessary to move the carriages.

18 designates an adjustable flush board and 17 a gangway or platform a section of which may be provided on each carriage.

Below the rail 1, I may arrange perforated pipes 20 which are connected with a water-pipe or with the upper level of the stream and serve to wash out or flush the chamber under the rail.

While the horizontally swinging pressure arm may, as shown, be attached to the front edge of the end carriage, it will, nevertheless be apparent that such a means for operating the carriages by the energy of the stream may be provided at any point on the carriage, or in fact, on any of the carriages.

While the chamber in the bank of the stream, into which the retaining carriages are drawn, is referred to as being in only one of the banks, it is clearly a part of my invention to provide a similar chamber, with similar appurtenant channels and operating devices, in the other bank.

It will be obvious that the features of construction described above are applicable to gates such as are used for locks.

It should be understood that I do not de-

sire to be limited to the exact details of construction shown and described, for obvious modifications will occur to a person skilled in the art.

I desire to claim and to secure by Letters Patent:—

1. In a plant of the character described, the combination of a rail disposed adjacent the bed of a stream and transversely of the direction of flow thereof, said rail having a downwardly projecting portion, and a retaining wall supported in operative position in the stream and provided with means disposed beneath said rail and bearing on the downwardly projecting portion of said rail for maintaining said wall in position against the force exerted by the water on the upstream side thereof tending to move said retaining wall downstream.

2. In a plant of the character described, the combination of a rail disposed adjacent the bed of a stream and transversely of the direction of flow thereof, said rail having a downwardly projecting portion, and a plurality of movable retaining walls, each of said walls supported in operative position being provided with means disposed beneath said rail and engageable with the downwardly projecting portion of said rail for guiding said retaining wall in its movement and for maintaining the wall in position against the action of a force tending to move the wall downstream.

3. In a plant of the character described, the combination of a rail disposed adjacent the bed of a stream and transversely of the direction of flow thereof, said rail having a downwardly projecting portion, a plurality of carriages movable along the bed of the stream, each of said carriages being provided with means disposed beneath said rail and engageable with said downwardly projecting portion on the upstream side thereof for guiding said carriage in its movement, and a pressure wall carried by an end one of said carriages and disposed at such an angle to the direction of flow of the stream as to be capable of causing movement of said carriage transversely of the stream through the action of flowing water on said pressure wall.

4. In a plant of the character described, the combination of a rail disposed adjacent the bed of a stream and transversely of the direction of flow thereof, said rail having a downwardly projecting portion, a plurality of carriages constituting a platform movable transversely along the bed of the stream, each of said carriages being provided with means disposed beneath said rail and engageable with the downwardly projecting portion of said rail to guide said carriage and retain the same in position against action of any force tending to move said carriage downstream, and a pressure wall

- associated with an end one of said carriages and movable relatively to such carriage to a position wherein the flowing water of the stream causes movement of the carriage 5 transversely of the stream.
5. In combination, a weir or gate supported in operative position in a stream and transversely of the direction of flow thereof, and means for retaining said weir in 10 operative position in the stream against a force tending to move the weir downstream, said retaining means comprising an element disposed in fixed position at the bed of the stream and provided with a downwardly 15 extending projection, and an element associated with said weir and extending beneath a portion of said first element said second element having a portion engageable with said projection on the upstream side thereof.
10. 6. In combination, guide means secured in position adjacent the bed of a stream and transversely of the direction of flow thereof, a carriage movable across said stream and having means coöperating with said guide 20 means for guiding said carriage in its transverse movement, the bank of said stream being provided with a chamber into which said carriage is movable, and means for applying pressure due to the head of water on the upstream side of said guide means for moving said carriage from said chamber.
7. In combination, a gate or dam structure, and means for retaining said structure in position in a stream, said means comprising a fixed element forming a portion of the 35 bed of the stream and comprising a body portion and a downwardly extending projection therefrom out of the path of the flowing stream, and an element associated with 40 said dam structure and bearing against the upstream side of the downwardly extending projection of said first element.
8. In combination, a gate or dam structure, and means for retaining said structure 45 in position in a stream, said means comprising an element fixed in position adjacent the bed of the stream and comprising a body portion and a downwardly extending projection therefrom, and an element associated 50 with said dam structure and engageable with the upstream side of said downwardly projecting portion.
9. In combination, a carriage movable across a stream, means for guiding said carriage in its movement, the bank of said stream being provided with a chamber into 55 and out of which said carriage is movable, and means for causing water under pressure, due to the head of water in said stream, to 60 move said carriage from said chamber.
10. In combination, a gate or dam structure supported in operative position in a stream, an element fixed in position at the
- bed of the stream, the downstream side of said element constituting an apron-like portion spaced from the normal bed of the stream and over which the stream flows, a projection on the under side of said apron-like portion, and a part supported by said dam structure and coöperating with said projection to hold said dam structure against movement due to the water on the upstream side thereof. 65
11. In combination, a gate or dam structure supported in operative position in a stream transversely of the direction of flow thereof, an element fixed in position at the bed of the stream and having its downstream side spaced from the normal bed of the stream and constituting an artificial bed 80 over which the stream flows, said element being provided with a downwardly extending flange clear of the normal bed of the stream and out of the path of the flowing stream, and means associated with said dam structure and engaging the upstream side of 85 said flange for retaining said dam structure in position against forces tending to move said structure downstream. 90
12. In combination, a supporting structure supported in operative position in a stream and movable in a generally horizontal direction out of operative position, and means for guiding said structure in its movement and for retaining said structure in operative position against the action of forces tending to move said structure downstream, said means comprising an element associated with said structure and an element coöoperative with said first element and 95 fixed in position at the bed of the stream, said fixed element being incapable of affording a lodging place for debris or sediment moving along the bed of the stream when said structure is removed from operative 100 position. 105
13. In combination, a gate or dam structure supported in operative position in a stream, an element fixed in position at the bed of the stream, the downstream side of 110 said element constituting an apron-like portion spaced from the normal bed of the stream and over which the stream flows, an element constituting an abutment and located beneath said apron-like portion, and 115 a part supported by said dam structure and coöperating with said abutment to hold said dam structure against movement due to the water on the upstream side thereof. 120

In testimony whereof, I affix my signature in the presence of two witnesses.

JAKOB STOCKER.
